W. H. SAUVAGE

SLACK ADJUSTER

Filed May 17, 1924

Patented Aug. 10, 1926.

UNITED STATES PATENT OFFICE.

WILLIAM H. SAUVAGE, OF NEW YORK, N. Y., ASSIGNOR, BY MESNE ASSIGNMENTS, TO
THE GOULD COUPLER COMPANY, A CORPORATION OF MARYLAND.

SLACK ADJUSTER.

Application filed May 17, 1924. Serial No. 714,171.

This invention relates to improvements in slack adjusters and more particularly to slack adjusters adapted for use on six wheel trucks, although, it is, of course, understood that without material modification various features are applicable to the usual four-wheel trucks.

As is well-known to those familiar with the art, six wheel trucks have one live lever 10 and two dead levers or the intermediate lever is a combined dead and live lever, whereby as the power is applied to the live lever all three levers are moved to bring the brake shoes into engagement with the respective 15 pairs of wheels.

One of the objects of the present invention is to provide a simple and practical slack adjuster of the above general type which may be inexpensively manufactured and assembled and applied to brake rigging and trucks now in use without material alteration.

A further object is to provide mechanism of the above character which will be reliable and efficient to take up all of the excess 25 travel of the brake rigging connected with the truck at each complete application and release of the brakes.

Other objects will be in part obvious from the annexed drawing and in part indicated 30 in connection therewith by the following analysis of the invention.

This invention accordingly consists in the features of construction, combination of parts and in the unique relation of the members and in the relative proportioning and disposition thereof, all as more completely outlined herein.

To enable others skilled in the art so fully to comprehend the underlying features 40 in order that they may embody the same by numerous modifications in structure and relation contemplated by this invention, a drawing depicting a preferred form has been annexed as part of this disclosure.

Figure 1 is a side elevational view of 45 such parts of the brake rigging and slack adjuster mechanism as is necessary to understand the invention.

Figure 2 is a detail view. Referring now in detail to Figure 1, 1 indicates a live lever and 2 what will be termed the dead lever, although it is to be understood that this lever acts as a live lever for applying the brakes to the next adjacent set of wheels. The upper end of the live

lever is connected by means of a pull rod 3 to any suitable source of power while a connecting rod 4 is attached to the upper end of the dead lever 2. The lower ends of these levers 1 and 2 are connected by a 60 telescoping push rod comprising an internal member 5 and a tubular member 6, the latter terminating in an enlarged housing 7 provided with a plurality of permanent take up and holding means which, in the present 65 case, is preferably composed of a plurality of holding dogs 8 adapted to grip the rod 5 when held in canted position by means of the helical spring 10. Immediately above the tie rod 6 is an adjusting rod 11 which 70 extends between a pivot point 12 on the dead lever and a swivel yoke 13 on the live lever, shown in detail in Figure 2. Upon this rod 11 is a temporary take-up and holding mechanism which preferably includes a housing 75 14, slidably mounted on said rod, having a dog 15 held in canted position by means of a coiled spring 16 whereby it has a biting engagement with the rod 11 to prevent movement thereof in one direction but allows free 80 movement in the opposite direction as will be more fully hereinafter explained. Interposed between the housing 14 and the swiveled support 13 is a compression spring 17. The live lever is provided with a fulcrum 85 point 18 at which point is usually connected the brake shoe heads for carrying the shoes adapted to engage the periphery of the adjacent wheel. The same is true of the pivot point 20 on the dead lever 2.

Interposed between the point 18 and the central part of the adjusting rod 11 is an actuating rod 21, one end of which is bent downwardly and around the rod 11 and spaced from the housing 14 a distance adapted to ensure brake shoe clearance at all times on release of the brakes. When the brakes are applied the upper end of the live lever 1 moves toward the left and carries the loop formed in rod 21 into engagement with the housing 14. If excess travel takes place, due to wear of the parts, then this housing 14 is moved relatively towards the left to compress the spring 17 an exact amount equal to the excess travel. On release of the parts the live and dead levers are restored to normal position by the usual return spring and the bent over end 21 drops away from the housing 14 and allows the helical spring 17 to expand, but the dog 15 now has a biting 100 105 110 end.

gagement with this rod and it reacts against the swiveled connection 13 to force the same relatively towards the left and carry the rod 5 out of its tubular casing 6 past the dogs 8, 5 thus changing the effective length of this push rod 6 between the lower ends of the live and dead levers an amount corresponding to the excess travel.

From the above it will be seen that the 10 slack adjuster mechanism herein described operates to take up all of the excess travel temporarily on each application of the brakes and to permanently take up this excess travel on release of the brakes.

15 When it is necessary to restore the parts to normal position for the purpose of replacing worn brake shoes, then both sets of dogs or holding devices 8 and 15 are moved to a position normal to the axis of the rods with 20 which they co-act, thus permitting the rod 5 to telescope inwardly with respect to the part 6 and the housing 14 to slide along the rod 11.

25 The mechanism which is simple and practical in construction, reliable and efficient in use and operation, is well adapted to accomplish all of the objects herein set forth.

Without further analysis, the foregoing 30 will so fully reveal the gist of this invention that others can, by applying current knowledge, readily adapt it for various applications without omitting certain features that, from the standpoint of the prior art, fairly 35 constitute essential characteristics of the generic or specific aspects of this invention, and, therefore, such adaptations should and are intended to be comprehended within the meaning and range of equivalency of the following claims.

40 What I claim is:—

1. In an automatic slack adjuster mechanism, in combination, live and dead levers, a telescopic push rod connecting the lower ends of said levers, permanent take up and holding means associated therewith for holding the parts in adjusted position, an adjustable mechanism interposed between the live and dead levers including a temporary take up and holding mechanism, a spring 45 adapted to be compressed on excess travel during application of the brakes, and to expand on release of the brakes to change the effective length of said push rod and permanently take up and hold the excess travel.

50 2. In an automatic slack adjuster mechanism, in combination, live and dead levers, a telescopic push rod connecting the lower ends of said levers, permanent take up and holding mechanism associated therewith for holding the parts in adjusted position, adjusting mechanism connecting intermediate parts of said levers, including a rod extending from the live lever to the dead lever and pivotally connected with it, and a second rod 55 extending from the live lever to a portion of

said first mentioned rod, temporary take up and holding means mounted upon said first mentioned rod adapted to be actuated by the second mentioned rod on excess travel, and a spring associated with the first mentioned 70 rod adapted to be compressed on excess travel on application of the brakes, and to expand to actuate the permanent take up and holding mechanism when the brakes are released. 75

3. In an automatic slack adjuster mechanism, in combination, a telescopic push rod connecting the ends of said levers, including a permanent take up and holding mechanism, a second rod parallel thereto connecting the intermediate parts of said levers and having a temporary take up mechanism thereon, a spring associated with said temporary take up mechanism, when the same is actuated, means adapted to connect the live 80 lever with said temporary take up mechanism when excess travel occurs, to move the same along said rod to compress said spring, said spring re-acting upon said live lever to cause a relative movement thereof when the 85 brakes are released and a relative adjustment of the telescopic push rod connecting the lower ends of said levers. 90

4. In an automatic slack adjuster mechanism, in combination, a live lever, a combined live and dead lever, a push rod connecting the said levers, an adjusting rod parallel thereto connecting the intermediate parts of said levers and a third rod substantially parallel to the first interposed between the live lever and an intermediate part of said second rod, a spring adapted to be compressed on excess travel of the brakes during the application thereof, said spring being adapted to expand on release of the 105 brakes, and to cause an adjustment in the first mentioned rod. 110

5. In an automatic slack adjuster mechanism, in combination, a live lever, a combined live and dead lever, a push rod connecting the said levers, an adjusting rod parallel thereto connecting the intermediate parts of said levers and a third rod substantially parallel to the first interposed between the live lever and an intermediate part of said second rod, a spring adapted to be compressed on excess travel of the brakes during the application thereof, said spring being adapted to expand on release of the 115 brakes, and to cause an adjustment in the first mentioned rod, said first mentioned rod having a solid part and a tubular part and a plurality of holding dogs carried by the tubular part adapted to engage the solid part and to prevent relative movement 120 thereof during the application of the brakes. 125

In witness whereof I have signed my name.

WILLIAM H. SAUVAGE,
